JAMES F. BOYLE, OF NEW HAVEN, CONNECTICUT, AND ADRIAN VAN MUFFLING, OF NEW YORK, N. Y., ASSIGNEES TO AIR CRUISERS, INC., OF NEW YORK, N. Y., A CORPORATION OF DELAWARE

PNEUMATIC WATER CRAFT

Application filed July 19, 1929. Serial No. 379,393.

This invention relates to pneumatic or collapsible gas-inflatable boats, life-rafts and similar floatation apparatus and is more particularly directed to the provision of means for supporting oars, paddles or other propelling elements.

At present, in boats or other apparatus composed of rubber or rubberized fabric, which are adapted to be inflated for use by 10 the introduction of air or other gas to suitable chambers or cells embodied therein, no satisfactory provision is made for the use of oars, paddles or other propelling devices therewith. A common expedient is to employ 15 a rope loop as an oarlock, the rope being secured to the wall or side of the boat or the like, by means of a fabric patch cemented thereto. At best, this is more or less of a makeshift arrangement. Apart 20 from the rapid wear of the rope in normal use, the attaching means and the loop itself frequently fail under the strains to which they are subjected by the manipulation of the oars in a heavy sea. Further, 25 in the use of a rope loop, as described, an oar must be inserted therein from its grip end. Obviously, this is objectionable in 30 shipping and unshipping oars, especially under emergency conditions, when the required handling of the oar in order to locate 35 it within the loop might result in its loss.

It has been proposed to provide sockets or bearing members for oar-locks of the regulation type supported outboard, but these 35 present difficulties in mounting, and in the folding and stowage of the boat which make their use impractical.

Therefore it is the general object of this invention to provide a simple, practical and 40 efficient means for supporting an oar, paddle or other propelling instrument from the wall or side of a pneumatic boat, raft or the like.

More specifically, it is the object of our 45 invention to provide means whereby an oarlock of the conventional design, or other support for a propelling instrument may be utilized in conjunction with the employment of a collapsible or gas inflatable marine vehicle.

As valve fittings are essential for the inflation and deflation of pneumatic water craft and such fittings are so embodied therein as to virtually become an integral part of their structure with all of the advantages flowing therefrom, it is a further object of our invention to provide for the utilization of such fittings as supporting means for oar-locks and other instrumentalities of similar functions.

Other objects and advantages flowing from the practicing of this invention will doubtless become apparent as the description proceeds and we would have it understood that we reserve unto ourselves all rights to 65 the full range of equivalents, both in structure and in use, to which we may be entitled under this invention in its broadest aspect.

For the purpose of the present disclosure, we have elected to show and describe certain preferred embodiments of our invention. Our invention, however, may take other forms without departing from the spirit and scope thereof as defined by the appended claims.

In the accompanying drawings, Figure 1 is a top plan view of a fragment of the side wall of a pneumatic boat, in which the present invention is incorporated.

Figure 2 is an enlarged sectional elevation 80 in the line *a*—*a* of Figure 1.

Figure 3 is a view, similar to Figure 2, of a modified form of the structure shown in Figures 1 and 2.

Figure 4 is a top plan view in line *b*—*b* 85 of Figure 3, and

Figure 5 is a detail of structure common to the forms of the invention shown in the preceding figures.

Referring now to the drawings in detail 90 in which like characters of reference are employed to designate similar parts in the several views, 7 indicates a valve fitting of metal or other suitable material, which is usually annular in form and provided with 95 a central bore, threaded at 8. At its upper end, the said fitting has a preferably integral circumferential flange or extension 9, which, when the body portion of said fitting is located within a suitable aperture cut in 100

the wall 10 of the boat, bears upon the material surrounding such aperture and to which it is permanently attached by cementing. A piece of rubber or similar material 11, of greater diameter than said flange is superposed thereon and cemented thereto and to the adjacent portion of the wall of the boat, it being apparent that said latter material 11, which is usually termed a patch is apertured, as at 11^a.

For the inflation operation, the nipple or nozzle of an air pump or gas bottle is threaded into said fitting, an externally threaded plug or stopper being seated in said fitting when inflation has been completed. The valve fitting and the method of making it virtually an integral part of the boat structure as it depends within the wall structure or gas chamber are well known in the art.

In the present invention, in lieu of the ordinary form of plug or stopper, we employ a valve sealing member which embodies an externally threaded plug or body portion 12 which has a preferably cylindrical dependent portion or stem 13 of a diameter to permit it to be inserted through the fitting 7 for seating the plug portion 12 in threaded engagement therewith, through the medium of the preferably integral finger grips or wings 14.

As will be observed, a central bore 15 extends from the top of said member to a point adjacent the lower end of the aforementioned dependent stem 13, the wall of said bore near its lower end being preferably provided with a circumferential groove 16.

The said bore 15 forms a socket for the reception of the stem 17 of an oar-lock of a conventional design, said stem, being peripherally grooved, as at 18, adjacent its lower end to provide a seat for the annular spring 19, this spring being placed in compression as the stem of the oar-lock is inserted in the plug member and expanding into the recess 16 to retain the oar-lock in its socket, it being obvious that while the oar-lock is thereby held against longitudinal movement relative to the socket, it is free to rotate or revolve therein.

In the embodiment of the invention illustrated in Figures 3 and 4, the wings 14 of the plug are dispensed with, said plug being threaded into sealing position by grasping the arms 20 of the oar-lock which is connectible to the plug for this operation. For making the required connection, so that the plug and the oar-lock may be rotated as a unit, we employ a pin 21 which is adapted to be seated in the vertical bore 22, located between the periphery of the plug 12 and its central bore 15, when the hole 23 in the enlarged base or bearing surface 24 of the oar-lock is brought into registration therewith. The pin, which may embody an eye 25, is

preferably connected to the oar-lock by a chain 26 or other flexible means.

When the plug has been threaded into sealing position in the fitting 7, the pin is withdrawn from the registering openings 70 and the bearing surface or base 24 of the plug is rendered capable of free rotary movement relative to the supporting surface or head of the plug.

In lieu of the interconnection of the plug 75 and the oar-lock by the pin 21, the former may have a slot provided in its top in which a hub or radial pin or extension on the base of the oar-lock may enter to interlock the plug and oar-lock for the fitting sealing operation, the hub being disengaged from the slot by raising and simultaneously rotating the oar-lock through a small arc. The hub will then ride upon the remaining unbroken surface of the plug, the arcuate movement 85 obtainable being ample to meet any range required by a rowing stroke.

Where it may be found to be desirable, the fitting 7 may embody a seat for a gasket or washer with which the base of the body 90 portion of the sealing member may engage to form an hermetic joint.

Manifestly, the sealing member may take other forms than shown and our invention may be practiced in conjunction with fittings of different types, attached to the boat or other water craft in various ways, it being understood, of course, that those valve fittings which are designed to function as receivers for the combination plug and oar-lock socket members will be properly located relative to the ends of the craft to admit of propulsion by rowing in the usual manner.

Valve fittings may also be located in the stern or at one end of a double-end craft which may receive a combination plug and connector for an outboard motor, or a special form of oar-lock for a sweep or scull. Again, a socket member for an oar-lock may be incorporated in a boat structure independently of the valve fitting 7, in which event the head of the socket member, similarly to said fitting, will have a peripheral flange for attachment to the boat in the manner heretofore described, although the combination plug and oar-lock socket is preferable for many, obviously, practical reasons.

Claims:

1. A sealing device for an air inlet for use in pneumatic water craft embodying a socket adapted to receive and house the stem of an oar-lock, said stem being rotatable within said socket.
2. A sealing device for a fitting whereby a gas inflatable water craft may be inflated or deflated, embodying a socket and means locatable within said socket for supporting a propelling instrument for such craft.

3. A sealing device for an air inlet of an inflatable water craft, embodying a socket for the reception of a device for supporting a propelling instrument for such craft and means for locating said sealing device in sealing position.

4. A sealing device for an air inlet of an inflatable water craft, embodying a body portion adapted for threaded engagement with said inlet, said body portion having an axial extension and a bore disposed longitudinally of said body portion and said extension and terminating inwardly of the end of the latter to form a socket for the reception of a support for a propelling instrument for such craft.

5. A sealing device for an air inlet of an inflatable water craft, embodying a body portion adapted for threaded engagement with said inlet, said body portion having an axial extension, a bore extending from the top of said body portion to a point above the lower end of said extension to form a socket for the reception of a support for a propelling instrument for such craft and means projecting above the top surface of the body portion of said device whereby said device may be engaged with and disengaged from said inlet.

6. The combination with a sealing plug for an air inlet in a pneumatic water craft of an oar-lock rotatably connected to said plug and means for retaining said oar-lock against longitudinal movement relative to said plug.

7. A combination air passage seal and oar-lock socket for pneumatic water craft, comprising a body portion adapted to function as a seal for said passage, an axial extension dependent upon said body portion, a bore extending through said body portion and into said extension to a point above the lower end thereof, said bore being adapted to receive the stem of an oarlock, and means integral with said body portion for locating the same in sealing position relative to said passage.

8. A combination air passage seal and oar-lock socket for pneumatic water craft, comprising a body portion adapted to function as a seal for said passage, an axial extension dependent upon said body portion, a bore extending through said body portion, and into said extension to a point above the lower end thereof to an oar-lock having its stem disposed for rotation within said bore and means detachably connectable to said body portion and to said oar-lock to interlock said elements whereby they may be rotated relative to said passage as a unit, the disconnection of said body portion and said oar-lock permitting said oar-lock to be rotated relative to said body portion.
